UNITED STATES PATENT OFFICE.

WALTER CHAUNCEY CAMP, OF NEW YORK, N. Y., ASSIGNOR TO THE NEW HAVEN CLOCK COMPANY, OF NEW HAVEN, CONNECTICUT.

DESIGN FOR A CLOCK-CASE AND CALENDAR.

SPECIFICATION forming part of Design No. 16,938, dated October 12, 1886.

Application filed July 21, 1886. Serial No. 208,695. Term of patent 7 years.

To all whom it may concern:

Be it known that I, WALTER C. CAMP, residing at New York, in the county of New York and State of New York, have invented and produced a new and original Design for a Combined Clock and Hand-Calendar Case; and I do declare the following to be a full, clear, and exact description of the same, reference being had to the accompanying drawing, which forms a part of this specification.

The accompanying drawing is a view in elevation of my newly-designed clock and hand-calendar case.

The leading feature of my design is a combined clock and hand-calendar case having a central time-dial and calendar-openings located in the case and above and below such time dial.

The case consists of a vertical upright body, A, a flat pyramidal top, B, and a base, C, of similar shape. The body of the case is provided with a central time-dial opening, D, and with an oblong or oval calendar-opening, E, located above, and with two similar calendar-openings, F and G, located in the same plane and below such time-dial opening.

H is the time-dial.

I are calendar-tapes exposed through the calendar-openings. J are frames inclosing such calendar-openings.

K are knobs projecting outward from the body and top of the case.

As herein shown, the days of the month are displayed through the openings E and the days of the week and the months of the year through the openings E and F, respectively.

What I claim is—

The design for a combined clock-case and hand-calendar herein shown and described, the same consisting of a case having a vertical upright body and a top and base, and having a central dial and openings located above and below the same, and also having knobs projecting outward from it.

In testimony whereof I have signed this specification in the presence of two subscribing witnesses.

WALTER CHAUNCEY CAMP.
